UNITED STATES PATENT OFFICE.

HENRY LINCOLN BEACH, OF NEW YORK, N. Y.

REMINDER SIGNAL.

Application filed October 12, 1922. Serial No. 594,127.

To all whom it may concern:

Be it known that I, HENRY LINCOLN BEACH, a citizen of the United States of America, and a resident of the city of New York, borough of Manhattan, in the county

and State of New York, have invented a new and Improved Reminder Signal, of which the following is a description.

My invention relates to a device constituting a signal adapted to be attached to the user's wearing apparel or placed in any conspicuous location in office, home, or elsewhere whenever there is anything important to be remembered or performed. When the device has functioned as a reminder the device may be closed or restored to the pocket or otherwise inconspicuously carried on the person.

The general object of my invention is to provide an effective device of the indicated character efficient for its purpose of actively imparting to the owner recollection of any intended action.

A further object is to impel performance of any intended action.

The nature of the invention and its distinguishing features and characteristics will clearly appear as the description proceeds.

Reference is to be had to the accompanying drawings forming a part of this specification, it being understood that the drawings are merely illustrative of one example of the invention.

Figure 1 is a front perspective view of a reminder device showing the same closed;

Figure 2 is a similar device open with the fastening pencil in the detached position;

Figure 3 is a rear perspective view of the reminder device closed;

Figure 4 is an enlarged transverse vertical section as indicated by the line 4-4, Figure 3; and

Figure 5 is a horizontal section as indicated by the line 5-5, Figure 4.

In carrying out my invention in practice a case is provided consisting of a back 10 and a front 11, the same being united along one edge by a suitable hinge 12 so that the front may swing to a closed position as in Figure 1 against the back or swing openly

to align with the back as in Figure 2. On the edge of the front opposite the hinge 12 is a knuckle 14, there being spaced knuckles 13 and 113 on the back 10 at the corresponding edge adapted to receive the knuckle 14 between them so that the bores of the

knuckles will align and may receive the fastening pin which preferably is in the form of a pencil, 15, the casing of which may include a telescoping section 115 carrying the lead.

On the back of the described case is a suitable means to fasten the device to a coat lapel or other portion of the garment. The fastening means may include a pin or a clip, or both. In the illustrated example I have shown a clip 16 integral with the back and disposed behind the latter. Integral with the lower edge of the clip is a pin 17 adapted to be engaged beneath a keeper 18. The back may have a spur 19 stamped rearwardly and the clip 16 may have an opposed spur or tongue 20 stamped forwardly adjacent to the spur 19 so that the clip may be caused to positively hold the device on the lapel, for example. Or, if desired, the pin 17 alone may be utilized as the fastening means. The clip 16 in addition may act as a prop, or as an easel support for the case for standing it on a table or on a desk if the reminder is wished to be kept on the desk instead of carrying it on the person. The front 11, when the device is stood on the table or desk, may be opened and allowed to lie open on the table or desk to display a written matter inscribed or placed on the inner face of said front, the lowered front thus acting as a base for the back 10 and coacting with the clip 16 to support the device in open position.

In practice the device at the exterior or interior or both, may bear a display signal or symbol; for example, Remind me, as illustrated at 11, Figures 1 and 2.

The interior of back or front, or both, in practice may have a celluloid or other suitable writing surface, as illustrated at 21, whereon the intended action may be indicated; but reliance need not be placed in this feature, due to the fact that the device itself by its conspicuous presence alone and noticed by the owner or pointed out to him by friends or office assistants, or stared at by strangers, is sufficient in itself for his recollection or further reference to memos.

I would state in conclusion that while the illustrated example constitutes a practical embodiment of my invention, I do not limit myself strictly to the exact details herein illustrated, since, manifestly, the same can be considerably varied without departure

from the spirit of the invention as defined in the appended claims.

Having thus described my invention, I claim:

- 5 1. A reminder device comprising a casing composed of a front and a back hinged together at one end, a removable means at the opposite end for retaining the front and the back closed, a clip on said back, and opposed spurs projecting from the clip and the back for retaining the device on the edge of a garment.
- 10 2. A reminder device comprising a casing composed of a front and a back hinged together at one end, a clip on said back, said clip merging into a fastening pin turned

upwardly and a keeper pressed out of the clip adjacent its fixed end for receiving the front end of said fastening pin.

- 20 3. A reminder device having a front and back hinged together at the lower ends thereof, a clip secured to said back and having a free end terminating in a plane adjacent the plane of said hinged lower ends, said clip adapted to be attached to a garment or to constitute a prop when the device is stood upon a support with said hinged ends lowermost, and the said front when lowered adapted to lie on said support to constitute a base for the back and to co-act with said prop in sustaining the device.

HENRY LINCOLN BEACH.
